AUDLEY E. HARNISBERGER, OF CHICAGO, ILLINOIS, ASSIGNOR TO GYRO PROCESS COMPANY, OF DETROIT, MICHIGAN, A CORPORATION OF MICHIGAN

TUBULAR HEATER

Application filed May 9, 1930. Serial No. 451,021.

This invention relates to improvements in tubular heaters, and has particular reference to improvements in tubular oil cracking stills wherein vaporized oils are subjected to high 5 temperatures to effect their molecular decomposition.

It is a common practice to pass vaporized oils in an elongated stream of restricted cross-section through the tubular passes, banks or 10 coils of an oil heater wherein the oils are brought to cracking temperatures which are frequently in excess of 1000° F. The oil vapors in passing through the externally heated pipes or tubes of such apparatus contact with the heated walls while traveling at 15 high velocity so that heat exchange takes place, the temperature of the tube walls and the velocity of the vapors having an important bearing on the rate of heat transfer. It 20 has been observed that in high temperature oil cracking heaters wherein oil in the vapor phase is heated to conversion temperatures, for example, between 1000° and 1200° F., not only are low boiling point oils of gasoline 25 range produced from higher boiling oils, but in addition there are also produced large quantities of fixed gas and free carbon, the gas being discharged from the heaters with the cracked vaporized products while the 30 carbon tends, at least, in part, to produce a hardened encrustation or coating on the inner walls of the heater tubes which interferes with the heating efficiency of such tubes and, also, results in relatively short life thereof.

35 This condition is thought to be due to the fact that while the oil vapor is passing through a highly heated tube the annular film or stratum of the oil vapor nearest or in contact with the inner wall of the tube is 40 overheated. That is to say, that portion of the oil vapor which contacts directly with the highly heated surfaces of the heater tubes attains a temperature considerably above the desired average or mean cracking temperature, 45 with the result that this portion of the oil vapor is overly heated producing therein violent splitting or decomposition reactions which produce the fixed or permanent gas and carbon deposition. Oil is a relatively 50 poor conductor for heat and as a result the oil

in the center or axial portion of the vapor stream passing through the heater tubes is, in fact, underheated insofar as a desired cracking temperature is concerned. This condition results in a low rate of cracking of 55 the oil vapor for each passage of the latter through the heater, with the result that large quantities of recycle stock are produced which must be again passed through the 60 heater for additional treatment.

To improve this condition it has been proposed heretofore to provide oil converters with tubes of relatively small diameter in order to provide but small volumes of oil vapor in any one of such tubes in comparison 65 with the heating surface present. Small tubes, however, lead to mechanical difficulties, particularly in high temperature apparatus wherein furnace temperatures of the order of 1500 to 2000° F. are employed. It 70 has also been suggested to employ tubes of larger diameter which are capable of withstanding the severe furnace temperatures without rapid deterioration and to provide the interiors of such tubes with longitudinally 75 extending cores which restrict the internal cross-sectional area of the tubes, which provide higher vapor velocities and limit the vapor in any one tube.

While these expediences have improved to 80 some degree the heating of oil vapor in a more uniform manner to a desired cracking temperature, the fundamental objections above noted with respect to lack of uniformity of heating the entire mass of oil vapor 85 passing through the tubes still obtains, with the result that carbon deposition persists in the converter tubes and fixed gas formation is unduly high.

I have succeeded in materially improving 90 these conditions in more uniformly heating the oil vapor passing through an externally heated tubular converter by providing the tubes of such converters with longitudinally 95 extending cores, wherein the cores are formed externally with helical webs or fins so proportioned that they do not contact with the inner walls of such tubes, the said helical webs, fins or baffles serving for a somewhat turbulent flow of the oil vapor through the an- 100

nular vapor passages of the tubes, enabling all portions of the oil vapor to contact with the highly heated inner surfaces of the tubes and avoiding specifically stratification of the oil vapor during its passage through such tubes.

For a further understanding of the invention reference is to be had to the following description and the accompanying drawing wherein:

10 Figure 1 is a vertical longitudinal sectional view taken through a tubular oil converter formed in accordance with the present invention,

15 Figure 2 is a transverse, sectional view on the line 2—2 of Figure 1, and

Figure 3 is a detail perspective view of the core construction.

Referring more particularly to the drawing, the numeral 1 designates a tube of the type used in connection with oil heaters or converters. These tubes are usually mounted within the masonry setting of a furnace (not shown) and the tube is preferably formed from ferrous alloys which permit the walls thereof to successfully withstand relatively high furnace temperatures for extended periods of operation without mechanical failure. These tubes are frequently formed from chromium alloys or other oxidation resisting metals and, again, ordinary steel tubes are specially treated or calorized to render them substantially immune to the action of high temperature furnace gases. Oil vapors are passed longitudinally through the tube when the latter is in active operation, the external temperature surrounding the tube being sufficient to heat the oil vapor to a cracking temperature in excess of 1000° F.

40 To improve heat transfer between the oil vapor and the heated walls of the tube 1, the latter is provided with a longitudinally extending core 2. This core consists usually of a suitable length of pipe which may be 45 formed from the same materials as those used in the construction of the tube 1. The inner pipe or core 2 is considerably smaller in diameter than the inside diameter of the pipe or tube 1 so that there is provided a longitudinally extending substantially annular space 50 3 between the adjacent walls of the tube 1 and the core 2 through which are passed the oil vapors to be subjected to heat treatment. The core 2 is supported longitudinally and 55 axially within the tube 1 and spaced from the inner walls of the latter by means of legs 4 which engage with the under surfaces of the tube 1. The legs are arranged at the ends of the core 2 and due to their formation offer 60 minimum obstruction to uninterrupted vapor flow through the space 3.

The outstanding feature of the present invention resides in providing the core 2 with the helical rib, fin or web 5. In practice it is 65 customary to form the element 5 from mate-

rial known as welding rod, which may be wrapped around the outer wall of the core, as shown, and permanently secured in position by fusing or welding. Attention is particularly directed to the fact that the baffle 5 is 70 so dimensioned that it does not contact with the inner wall 6 of the tube 1, but is spaced from the latter as disclosed. This provides for the high velocity flow of oil vapor at low pressure through the tube or vapor space 3 75 and eliminates specifically high back pressures. The baffle provides for a helical and somewhat turbulent flow of the oil vapor through the space 3 so that stratification of the oil vapor is prevented and therefore a 80 uniform contact is obtained between all parts of the oil vapor and the heated surfaces of the tube 1.

By thus uniformly heating the oil vapor, converting apparatus is provided in which 85 the evils due to over-cracking are minimized, namely, gas formation and carbon deposit and, conversely, the evils of under-cracking are correspondingly minimized and higher 90 yields of converted products produced. The core 2 may be positioned so as to extend but part way of the length of the tube 1 or it may extend the full length of such a tube or a tube bank in which the tube 1 forms a part. I 95 find it preferable to place the spirally or helically wrapped core in the tube or tubes occupying the high temperature zone of the converter, particularly in converters where a marked temperature differential exists in the furnace gases initially contacting with the converter tubes and the gases discharged from contact with such tubes. In the relatively cooler areas of such a heater a plain core or, in fact, no core at all may be used. 100 As a general rule, the core is placed in that portion of a tubular vapor phase oil converter 105 wherein carbon deposition is apt to take place.

What is claimed is:

1. In apparatus for cracking oil in the vapor phase, a furnace tube adapted for the 110 passage of oil vapor, a core positioned stationarily and longitudinally in said tube and supported therein in spaced relation from the inner walls of the tube to define a longitudinally extending substantially annular oil vapor passageway, and a rod wrapped helically around the outer surface of said core and permanently secured thereto, said rod having its outer surfaces terminated in spaced relationship from the inner walls of the tube, said 115 helically wrapped rod serving to impart a substantially swirling movement to the oil vapor passing through said tube to effect the uniform heating and contact thereof with the walls of the tube.

2. In apparatus for cracking oil in the vapor phase, a furnace tube through which oil vapor is adapted to be passed and subjected to cracking temperatures, a core positioned stationarily and axially within said 120

pipe member and comprising a straight elongated cylindrical body of substantially uniform diameter throughout its length, a rod wound helically around the outer surface of said body and permanently secured thereto, the outer surfaces of said rod terminating in spaced relationship from the inner walls of said tube, and radial supports projecting from said body and engaging with the inner walls of said tube to position said body centrally and axially of the tube.

3. A core for oil vapor cracking tubes, comprising a straight elongated cylindrical body of substantially uniform diameter throughout its length and adapted to be stationarily positioned in a tube, a rod wrapped helically around the outer surface of said body and permanently secured in fixed relationship therewith by welding, and a plurality of spacing lugs projecting radially from said body and disposed between the windings of said rod.

4. A core for tubes for converting oil in the vapor phase comprising a cylindrical body of substantially uniform diameter, a substantially helical baffle positioned externally of said body, supporting means secured externally of said body and adapted to support the same in spaced relation with and in a converting tube, said supporting means having a greater radial dimension measured from the axis of the body than any of the generatrices of said baffle.

In testimony whereof I affix my signature.
